UNITED STATES PATENT OFFICE

121,577

DESIGN FOR A PROFILING MACHINE

Frank S. Shields, Jamaica, N. Y.

Application April 9, 1940, Serial No. 91,561

Term of patent 14 years

To all whom it may concern:

Be it known that I, Frank S. Shields, a citizen of the United States of America, residing in the county of Queens and State of New York, have invented a new, original, and ornamental Design for a Profiling Machine, of which the following is a specification, reference being had to the accompanying drawings, forming a part thereof.

Figure 1 is a front elevational view of a profiling machine showing my new design;

Figure 2 is a side elevational view thereof; and
Figure 3 is a rear elevational view thereof.

I claim:

The ornamental design for a profiling machine,
as shown.

FRANK S. SHIELDS.
